Attorney

UNITED STATES PATENT OFFICE.

EDGAR E. SCHLESINGER, OF CHICAGO, ILLINOIS, ASSIGNOR TO UNION METAL PRODUCTS COMPANY, OF CHICAGO, ILLINOIS, A CORPORATION OF DELAWARE.

CAR-COUPLER-CENTERING DEVICE.

Application filed April 20, 1923. Serial No. 633,479.

To all whom it may concern:

Be it known that I, EDGAR E. SCHLESINGER, residing at Chicago, county of Cook, State of Illinois, and being a citizen of the 5 United States, have invented certain new and useful Improvements in Car-Coupler-Centering Devices, of which the following is a full, clear, and exact description, such as will enable others skilled in the art to 10 which it appertains to make and to use the same, reference being had to the accompanying drawings, which illustrate the preferred form of the invention, though it is to be understood that the invention is not 15 limited to the exact details of construction shown and described, as it is obvious that various modifications thereof within the scope of the claims will occur to persons skilled in the art.

20 Many railway cars are equipped with a carrier for supporting the coupler which is swingingly suspended by links from the striking casting, draft sill or other part of the car, so that when cars are uncoupled the 25 coupler is returned by gravity to substantially the center of the car, thus assuring the coupling of the couplers, eliminating the lateral stresses on the coupler due to impact or coupling and also obviating the 30 necessity of trainmen going between the cars to position the coupler for coupling. Such a device is called a combined coupler carrier and centering device and is illustrated in Sisson Patents No. 1,080,723, No. 35 1,080,724 and No. 1,080,725, all of December 9, 1913.

Formerly the couplers in general use had an enlarged portion at the rear end for attachment of the draft yoke which embraced 40 the draft gear. This enlarged rear end required that some means be provided to remove the carrier, or at least one end of it, from the car part before the coupler could be removed either horizontally or vertically. 45 Usually a removable pin or a bolt is provided which is held in place by a cotter pin or nut. Such contrivances have the ever present possibility of the pin coming out, because the cotter pin was not spread or the 50 nut was not tightened, which, of course, might permit the coupler to fall upon the track and wreck the train.

The American Railroad Association has adopted a standard coupler known as the type "D", which does not have the enlarged

rear portion before described, and, therefore, it is not necessary to provide means permitting the removal of the carrier before the coupler can be removed: in fact, the contrary is true. 60

The object of this invention is to so connect the carrier to a supporting swinging link that they cannot be disconnected from each other while they are in operative position on the car or while the coupler is in 65 service position on the car.

Another object is to so connect the device that the parts can be easily made, assembled on and removed from the car after the coupler is removed from its service position on the car. 70

When cars are passing over vertical curves in the track, and also when coupling by impact, the coupler raises from the carrier and the top of the coupler shank frequently hits the striking casting or dead block but it still is in service position on the car. 75

For simplicity of construction and interchangeability of parts, as well as assurance 80 that the device will be properly assembled, it might also be advisable to use my new arrangement where the link is connected to the striking casting. However, it may be economical to reduce the number of parts and 85 use a trunnion at one end of the link (see Fig. 6) and the headless pin arrangement at the other end. It is immaterial whether my new arrangement is used at the upper or lower end of a link or on one or both links, 90 or on both ends of both links, as my invention covers the improved means of connecting one end of a link to the cooperating adjacent part of the car, that is, the striking casting or the carrier. 95

In the drawings:

Fig. 1 is a side elevation of Fig. 2.

Fig. 2 is a front elevation of a combined carrier and centering device showing parts of the car broken away. The improved method of connecting the link to the parts of the car is also shown. 100

Fig. 3 is a cross section on line 3—3 of Fig. 2.

Fig. 4 is an enlarged detail of the link. 105

Fig. 5 is an enlarged detail of the headless pin.

Fig. 6 is an enlarged detail of a link with a trunnion at one end.

In the drawings the striking casting 1 is at- 110

tached to the draft sill 2 and the coupler 3 is supported by the carrier 4 by means of links 5. The coupler is retained in central position on the carry iron by lugs 6 which 5 also has a movable engagement with a slot 7 in the striking casting so as to limit the lateral movement of the carrier. The links 5 have a pivotal connection with the striking casting and carrier respectively so as to permit of a longitudinal swinging movement of 10 the carrier and it is in these particular connections and the relation of the associated parts that I claim an improvement.

The object of the invention is accomplished 15 by using a headless pin 8 which is inserted in perforation 17 provided in the link 5 so that it extends outwardly from either side of the link. The carrier 4 is provided with bearings 10 which engage these outwardly extending portions so as to form a 20 pivotal connection therewith. The carrier is further provided with walls 13 which are so positioned as to limit the longitudinal movement of the headless pin when in operative 25 position and these walls are provided with apertures 15. The device is assembled by raising the carrier 4 until aperture 15 is opposite the perforation 17 so that the pin may be inserted. The carrier 4 is then lowered 30 until the pin contacts with the bearings 10 so that the walls 13 prevent the longitudinal removal of the pin. When it is desired to disconnect the carrier from the link the carrier is raised a predetermined amount 35 until the pin 8 is opposite the opening 15. The distance between the upper surface of the coupler shank 18 and the under surface of the striking casting 19 is less than the required vertical movement of the end of the 40 carrier to permit the removal of the pin. The various parts are so positioned and dimensioned that after the coupler is removed 45 from the car the end of the carrier can be raised sufficiently to permit the removal of the pin. In the drawings the vertical distance between the carrier at 20 and the striking casting at 21 is more than the vertical distance between the coupler at 18 and the striking casting at 19, and also more than 50 the vertical movement necessary to register perforations 17 and 15. The walls 13 pre-

vent the longitudinal movement of the pin while the parts are in assembled operative position on the car.

The upper end of the link is provided with 55 a perforation 16 which engages a pin 8 and the striking casting has bearings and walls 11 and 12 and apertures 14 giving the same relation of parts and operating in substantially the same manner as heretofore described relative to the lower end of the link. 60

This application is a continuation in part of my application Serial No. 519,556, filed December 2, 1921.

I claim:

1. The combination, in a railway car, of a coupler, a swinging coupler carrier, a suspension link, and a headless pin pivotally connecting said carrier to said link, the end of said carrier bifurcated to straddle the link, 70 each portion of said bifurcated end having walls to limit the longitudinal movement of said pin.

2. The combination, in a railway car, of a coupler, a swinging coupler carrier, a suspension link, and a headless pin pivotally connecting said carrier to said link, the end of said carrier bifurcated to straddle the link, 75 each portion of said bifurcated end having walls to limit the longitudinal movement of said pin, and an aperture in one of said walls permitting the longitudinal removal of said pin upon elevation of the carrier a predetermined amount.

3. The combination, in a railway car, of a coupler, a coupler carrier swingingly suspended from another part of the car by suspension members, separate means for connecting the carrier to one of said suspension members, which means cannot be removed 90 while the coupler is mounted upon the carrier.

4. The combination, in a railway car, of a coupler, a coupler carrier swingingly suspended from another part of the car by suspension members, separate means for connecting the carrier to one of said suspension members, which means cannot be removed 95 while the device is in assembled operative position.

EDGAR E. SCHLESINGER.
